(57) **CLAIM**

The ornamental design for a side mirror for a vehicle, as shown and described.

DESCRIPTION

This application is related to the following co-pending application, of the inventor, filed on even date herewith: application Ser. No. 29/270,222, entitled "Surface Configuration of a Vehicle, Toy, and/or Other Replicas".

FIG. 1 is a front perspective view a first embodiment of a side mirror for a vehicle according to my novel design;

FIG. 2 is a rear perspective view thereof;

FIG. 3 is a front view thereof;

FIG. 4 is a rear view thereof;

FIG. 5 is a side view thereof;

FIG. 6 is a top view thereof; and

FIG. 7 is a bottom view thereof.

FIG. 8 is a front perspective view a second embodiment of the side mirror for a vehicle according to my novel design;

FIG. 9 is a rear perspective view thereof;

FIG. 10 is a front view thereof;

FIG. 11 is a rear view thereof;

FIG. 12 is a side view thereof;

FIG. 13 is a top view thereof; and,

FIG. 14 is a bottom view thereof.

The broken lines are for illustrative purposes only and form no part of the claimed design.
